DESIGN FOR AN ORNAMENT FOR HAND-BAGS OR THE LIKE

Frank X. Hiltenbrand, Weehawken, N. J., assignor to Harry Rosenfeld, Inc., New York, N. Y., a corporation of New York

Application September 26, 1946, Serial No. 133,592

Term of patent 7 years

(Cl. D87—2)

To all whom it may concern:

Be it known that I, Frank X. Hiltenbrand, a citizen of the United States, residing at Weehawken, in the county of Hudson and State of New Jersey, have invented a new, original, and ornamental Design for an Ornament for Handbags or the like, of which the following is a specification, reference being had to the accompanying drawing, forming part thereof.

In the drawing

Fig. 1 is a side elevational view of an ornament for handbags or the like, showing my new design;

Fig. 2 is a top plan view thereof.

I claim:

The ornamental design for an ornament for handbags or the like, substantially as shown.

FRANK X. HILLENBRAND.
